UNITED STATES PATENT OFFICE.

CARL WALCHNER, OF ERMADINGEN, SWITZERLAND, ASSIGNOR TO JACOB
EMANUEL, OF FRANKFORT-ON-THE-MAIN, GERMANY.

WINDOW.

No. 858,236.

Specification of Letters Patent.

Patented June 25, 1907.

Application filed March 14, 1905. Serial No. 250,119.

To all whom it may concern:

Be it known that I, CARL WALCHNER, a subject of the King of Würtemberg, and a resident of Ermadingen, Switzerland, have 5 invented certain new and useful Improvements in Windows, of which the following is a specification.

My invention relates to improvements in windows with sliding upper sashes and 10 swinging lower sashes, whereby it is rendered possible to open the lower sashes at will either inwardly or outwardly for cleaning the window with perfect safety.

The objects of my improvement are, first, 15 to provide a recess in the sill of the window frame; second, to provide a vertically movable supporting ledge, which has a tongue on its upper face and engages with its lower part in the recess of the frame sill; third, to provide 20 means for raising and lowering the supporting ledge; fourth, to provide the window frame on its internal faces at both sides and at the top with tongues; fifth, to provide the sliding upper sash with grooves on its external edge faces; sixth, to provide means for 25 raising and lowering the upper sash; seventh, to provide two lower sashes, which are normally guided by their grooves engaging the tongues of the frame and can be secured by 30 the upper sliding sash and the supporting ledge on pressing the latter upward, while on lowering the latter the two lower sashes will be released and allowed to drop; eighth, to provide external and internal windowhinges 35 and to so arrange them, that when the window is completely closed and the lower sash is in its upper position only the upper internal hinges are operative and when the lower sash is in its lowest position the external 40 hinges are operative while the members of the internal hinges are disconnected; and, ninth, to provide the supporting ledge with a dust and water guard. I attain these objects by the window illustrated in the accompanying drawing, in which—

Figure 1 is an internal view of the window in its closed state, Fig. 2 is an external view of the same in its closed state, Fig. 3 is a cross section through the same in its closed 50 state on the line A—A in Fig. 1, seen from left to right, Fig. 4 is a similar section, the lower sashes of the window being lowered and positioned to be opened inwardly; Fig. 5 is a similar section, the lower sashes being

lowered and positioned to be swung outwardly; Fig. 6 is an elevation of the lower internal left hinge, its loop being turned aside and the window being closed, Fig. 7 is a horizontal section through the line D—D in Fig. 5, Fig. 8 is an elevation of the lower external 60 right hinge, the lower sash being lowered and ready to be opened outwardly, Fig. 9 is a horizontal section through the line E—E in Fig. 8, Fig. 10 is an internal view of a part of the frame sill, the board d¹ being removed 65 to show the device for raising and lowering the supporting ledge, and Fig. 11 is a cross section through the frame sill and the supporting ledge on the line F—F in Fig. 10.

Similar letters of reference refer to similar 70 parts throughout the several views.

The window frame d is secured in the wall opening in any known manner. Its sill is so cut out as to form a longitudinal recess d² (see Figs. 3, 4 and 5), which in its middle is 75 widened out downwardly so as to leave sufficient space for a metallic plate n and a cam f (see Figs. 10 and 11). A supporting ledge h is so shaped, that its lower part can engage in the recess d², and a board d¹ is fastened on 80 the frame d for guiding the lower part of the supporting ledge h and for preventing it from shifting inwardly. The frame d is provided with tongues d³ on its internal faces at both sides and at the top. The two ends of the 85 supporting ledge h are provided with grooves, in which the tongues d³ of the frame d engage, so that the ledge h is guided not only in the recess d² but also by the tongues d³. The supporting ledge h is provided on its upper 90 face with a tongue h¹ in correspondence with the tongues d³ and moreover on its external side it is provided with a metallic dust and water guard m. This guard m is made sufficiently wide to overlap the sill even in the 95 uppermost position of the supporting ledge h, see Fig. 3. The cam f already mentioned above is fastened on a square part of a pin e (Fig. 11), which latter is mounted to turn in the metallic plate n and in a suitable bush in 100 the board d¹ and carries on the internal end a hand crank g.

In Figs. 10 and 11 the cam f occupies its lowermost position (see also Figs. 4 and 5), so that the supporting ledge h is lowered and 105 rests on the frame sill and the board d¹. The upper sash i is provided on its external edge faces with grooves i¹, in which the tongues

$d^3 d^3$ of the frame d engage, partly for vertically guiding the sash i and partly for tightening the top joint, in case the sash i is pressed upward. The upper sash i is arranged to be raised and lowered in any known manner, for example by means of a cord k led over suitable rollers and secured by a hook o (Figs. 3, 4 and 5).

The two lower sashes $c c$ are provided at the sides with grooves $c^1 c^1$ (Figs. 7 and 9) for the tongues $d^3 d^3$ of the frame d , at the bottom edge with grooves c^2 (Figs. 3, 4 and 5) for the tongue h^1 of the ledge h and at the top edges with tongues c^3 , which can engage in the lower groove i^1 of the upper sash i . It will be evident, that, when the lower sashes $c c$ rest on the supporting ledge h and the upper sash i on them, they can be safely guided by the lateral tongues $d^3 d^3$ of the frame d and they will be secured on being pressed upward by the cam f . For this reason the two lower sashes may be left without any fastening or locking device.

As already indicated above, the window is provided with external and internal hinges, which are constructed in the following manner: The pivots of the two upper internal hinges $a a$ are fastened on the frame d (Fig. 1) and those of the two upper external hinges $b b$ on the sashes $c c$ (Fig. 2). The former are made longer than the latter for a purpose, which will be presently explained. These hinges $a a$ and $b b$ are so disposed on the window, that the pivots of the internal hinges $a a$ completely engage in their loops (see Fig. 1), when the supporting ledge h is raised and the window thereby closed, while the pivots of the external hinges are at a certain height above their loops (see Fig. 2). The pivots of the two lower internal hinges $a^1 a^1$ are fastened on the sashes $c c$ and their loops are hinged to the frame d , so that they may be turned aside (Figs. 1, 5, 6 and 7). These lower internal hinges are so disposed, that, when the window is closed, their pivots are just above their loops and permit the latter to be turned in and out (Fig. 1). The pivots of the two upper internal hinges $a a$ are made so long, that they still remain in engagement with their loops on the supporting ledge h being lowered, provided, that the pivots of the two lower internal hinges $a^1 a^1$ engage in their loops and the latter support the two lower sashes $c c$. If, however, the loops of the two lower internal hinges $a^1 a^1$ are turned aside (Figs. 6 and 7) and the supporting ledge h is lowered by means of the hand crank g and the cam f , the two sashes $c c$ resting on the supporting ledge h will be further lowered, so that the pivots of the two upper internal hinges $a a$ withdraw from their loops. The pivots of the two upper external hinges $b b$ are made so short, that they remain just above their loops, in case the loops of the two lower internal hinges $a^1 a^1$ have been turned

and support the two sashes $c c$, after the supporting ledge h has been lowered. Only, when the loops of the two internal hinges $a^1 a^1$ are turned aside (Figs. 6 and 7) and the supporting ledge h is lowered, will the pivots of the two upper external hinges $b b$ engage in their loops.

The pivots of the two lower external hinges $b^1 b^1$ are fastened on the two lower sashes $c c$ and so disposed, that they can engage in their loops at the same time as the pivots of the upper external hinges engage in their loops. The loops of the two lower hinges $b^1 b^1$ are provided with shells $b^2 b^2$, which may be soldered or otherwise fastened on them and leave each a recess, in which a lock l fastened on the sash c (Fig. 11) can engage. The two locks $l l$ are so disposed, that they engage in the said recesses between the shells $b^2 b^2$ and the sashes $c c$, as long as the window is closed or the two lower sashes $c c$ are supported by the turned-on loops of the two lower internal hinges $a^1 a^1$. However, when these loops are turned aside and the two sashes $c c$ are so much lowered, that the pivots of the two lower external hinges $b^1 b^1$ engage in their loops, then the locks $l l$ will be clear from the shells $b^2 b^2$, see Fig. 8, and be ready to engage beneath the shells $b^2 b^2$.

The window is operated as follows: Normally the window is closed, so that the supporting ledge h occupies its uppermost position and presses the two lower sashes $c c$ against the upper sash i and the latter against the top of the frame d . Then the tongues $d^3 d^3 h^1 c^3$ of the frame d , the supporting ledge h and the two lower sashes $c c$ respectively, which engage in the respective grooves, will prevent the three sashes i and $c c$ from moving. When it is desired to open the window outwardly as usual, the loops of the two lower internal hinges $a^1 a^1$ are left in position out of alignment with their pivots (Figs. 6 and 7) and the hand crank g is turned to lower the supporting ledge h . Thereby the two lower sashes $c c$ are also lowered until the pivots of all the external hinges $b b$ and $b^1 b^1$ engage in their loops, while the pivots of the two upper internal hinges $a a$ withdraw from their loops and those of the two lower internal hinges $a^1 a^1$ remain without engagement with their loops. Therefore the two lower sashes $c c$ can be pushed outwardly and will turn around the pivots of the external hinges $b b$ and $b^1 b^1$. Then the upper sash i may be lowered by means of the cord k and allowed to rest on the supporting ledge h . In this position the sash i may serve as a guard to protect children or other people from leaning too much out of the window. Also the sash i will secure the two outwardly turned sashes $c c$ against motion under the action of a wind or the like. The two locks $l l$ having engaged beneath the two shells $b^2 b^2$ will prevent the two sashes from moving upward.

and thereby prevent the pivots of all the external hinges b b and b^1 b^1 from getting off their loops. x y are rabbeted ledges which are connected with the under side of the upper sashes and with the upper side of the supporting ledge respectively and which prevent the lower sashes, when the latter are partly lowered, from moving outward, and when they are wholly lowered, from moving inward. For again closing the window, it is only necessary to raise the upper sash i , to turn inwardly the two lower sashes c c and to turn the hand crank g in the opposite direction for raising the supporting ledge h . The loops of the two lower internal hinges a a^1 should always be turned aside when not in use. When it is desired to clean the window quite comfortably and with perfect safety, the loops of the two lower internal hinges a a^1 are turned to bring them in alinement with the pivots of said hinges and the hand crank g is turned to lower the supporting ledge h . Then the pivots of the two lower internal hinges will engage in their loops, while those of the two upper internal hinges still remain in engagement with their loops, but the pivots of all the external hinges b b and b^1 b^1 are out of engagement with their loops. Therefore the two lower sashes c c can be drawn inwardly and will turn around the pivots of the internal hinges a a and a^1 a^1 . In this position they can be cleaned. Also the upper sash i can be lowered and equally cleaned easily and safely.

What I claim as my invention, and desire to secure by Letters Patent, is:—

1. In a window of the class described, the combination with a frame, of a supporting ledge vertically guided therein and periodically resting on the sill, means for raising and lowering said supporting ledge, an upper sash vertically guided in said frame, means for raising and lowering said upper sash, a lower sash adapted to be vertically guided in said frame when resting on said supporting ledge, a plurality of external hinges, the pivots of which are adapted to engage in their loops only in the lowermost position of said supporting ledge, and a plurality of internal hinges, the pivot in the upper internal hinge being adapted to engage in its loop only in the uppermost and an intermediary position of said supporting ledge and either member of the lower internal hinges being adapted to be shifted aside when not required.

2. In a window of the class described, the combination with a frame, of a longitudinal recess in the sill of said frame, a supporting ledge vertically guided in said longitudinal recess and in said frame, a dust and water guard on the external side of said supporting ledge, a shaft mounted in the sill of said frame to turn, a cam and a hand crank on said shaft for raising and lowering said supporting ledge, an upper sash vertically guided

in said frame, means for raising and lowering said upper sash, a lower sash adapted to be vertically guided in said frame when resting on said supporting ledge, a plurality of external hinges, the pivots of which are adapted to engage in their loops only in the lowermost position of said supporting ledge, and a plurality of internal hinges, the pivots of which are adapted to engage in their loops only in the uppermost and an intermediary position of said supporting ledge and either member of the lower internal hinges being adapted to be shifted aside when not required.

3. In a window of the class described, the combination with a frame, of a supporting ledge vertically guided therein and periodically resting on the sill, means for raising and lowering said supporting ledge, an upper sash vertically guided in said frame, means for raising and lowering said upper sash, two lower sashes adapted to be vertically guided in said frame when resting on said supporting ledge, a plurality of external hinges, the pivots of which are adapted to engage in their loops only in the lowermost position of said supporting ledge, and a plurality of internal hinges, the pivots of which are adapted to engage in their loops only in the uppermost and an intermediary position of said supporting ledge and either member of the lower internal hinges being adapted to be shifted aside when not required.

4. In a window of the class described, the combination with a frame, of a longitudinal recess in the sill of said frame, a supporting ledge vertically guided in said longitudinal recess and in said frame, a dust and water guard on the external side of said supporting ledge, a shaft mounted in the sill of said frame to turn, a cam and a hand crank on said shaft for raising and lowering said supporting ledge, an upper sash vertically guided in said frame, means for raising and lowering said upper sash, two lower sashes adapted to be vertically guided in said frame when resting on said supporting ledge, a plurality of external hinges, the pivots of which are adapted to engage in their loops only in the lowermost position of said supporting ledge, and a plurality of internal hinges, the pivots of which are adapted to engage in their loops only in the uppermost and an intermediary position of said supporting ledge and either member of the lower internal hinges being adapted to be shifted aside when not required.

5. In a window of the class described, the combination with a frame, of a longitudinal recess in the sill of said frame, a supporting ledge vertically guided in said longitudinal recess and in said frame, a dust and water guard on the external side of said supporting ledge, a shaft mounted in the sill of said frame to turn, a cam on said shaft within a

- widened out part of said longitudinal recess and adapted to bear against said supporting ledge for raising and lowering same, a hand crank on said shaft, an upper sash vertically guided in said frame by means of tongues and grooves, means for raising and lowering said upper sash, two lower sashes adapted to be vertically guided in said frame by means of tongues and grooves when resting on said supporting ledge, a plurality of external hinges the pivots of which are adapted to engage in their loops only in the lowermost position of said supporting ledge, and a plurality of internal hinges, the pivots of which are adapted to engage in their loops only in the uppermost and an intermediary position of said supporting ledge and either member of the lower internal hinges being adapted to be turned aside when not required, said two lower sashes being adapted to engage said supporting ledge and said upper sash by means of tongues and grooves.
6. In a window of the class described, the combination of a frame, two independently movable sashes fitted within the frame, the lower sash comprising two sections each having hinge members on both its inner and outer faces adapted to engage with hinge members on the frame, and means for moving said lower sash vertically when closed, the parts being so arranged that when the lower sash is in its highest position all of the hinge members except those of the upper internal hinges are disengaged, and when said sash is in its lowest position, the members of the external hinges only are engaged, substantially as and for the purpose described.
7. In a window of the class described, the

combination of a frame, two sashes arranged within the frame, the lower sash comprising two sections each adapted to swing both outwardly and inwardly, means for moving the upper sash vertically, and independent means for raising and lowering the lower sash to effect a connection of the members of one set of hinges and disengagement of the members of the other set.

8. In a window of the class described, the combination of a frame, two sashes mounted in the frame, the lower sash being adapted to swing both outwardly and inwardly, independent sets of hinges for supporting said lower sash when swinging outwardly and inwardly, and means for raising the lower sash to disconnect it from one of said sets of hinges and holding said sash in such position.

9. In a window of the class described, the combination of a frame, two independently movable sashes fitted within the frame, the lower sash comprising two sections, two sets of hinges arranged on opposite sides of each section of the lower sash for supporting the sash when swinging outwardly and inwardly respectively, the frame members of the lower inner hinges being adapted to swing to and from alignment with the pivot members of said hinges, and means for moving the lower sash vertically when in closed position, substantially as and for the purpose described.

In testimony whereof I have signed my name to this specification in the presence of two subscribing witnesses.

CARL WALCHNER.
